UNITED STATES PATENT OFFICE.

JOSEPH E. STRAUB, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,270,986.

Specification of Letters Patent.

Patented July 2, 1918.

Application filed April 14, 1917. Serial No. 162,003.

To all whom it may concern:

Be it known that I, JOSEPH E. STRAUB, citizen of the United States, and resident of Ilion, in the county of Herkimer and State 5 of New York, have invented certain new and useful Improvements in Type-Writing Machines, of which the following is a specification.

My present invention relates to devices 10 for preventing the locking or arresting of the carriage of typewriting machines as a result of the defective setting or retracting of the tabulator stops, and more specifically is concerned with the provision of new and 15 improved devices that are commonly termed "full stroke devices" for use in connection with the key setting or retracting means for tabulating stops of the magazine style.

To the above and other ends which will 20 hereinafter appear, my invention consists in the features of construction, combinations of devices and arrangements of parts hereinafter described and particularly pointed out in the claims.

25 In the accompanying drawings which illustrate the preferred form of my invention,

Figure 1 is a fragmentary side elevation, partly in section, of a Monarch typewriting 30 machine embodying my invention.

Fig. 2 is a fragmentary perspective view of a front post.

Fig. 3 is a fragmentary front to rear vertical sectional view showing said invention 35 applied to the stop setting key of the tabulating mechanism.

Fig. 4 is a fragmentary view, corresponding to Fig. 3, but showing the full stroke devices in a different position.

40 Fig. 5 is an enlarged vertical sectional view, taken on the plane indicated by the dotted line $\alpha\alpha$ in Fig. 3 and looking in the direction of the arrows at said line.

Fig. 6 is a fragmentary detail view, partly 45 in section.

As appears from Fig. 1 the main frame of the Monarch machine comprises a base 1, posts 2, and a top plate 3, above which is arranged a platen 4 mounted on a carriage 5 that co-operates through anti-friction balls 6 with stationary track-ways 7 and 8. The carriage is urged to the left by a spring drum and its step-by-step movement is controlled by escapement devices (not shown).

55 Tabulating mechanism of the usual con-

struction is provided, said mechanism comprising a toothed bar 9 on which are mounted column-stops 10 that are adapted for co-operation with denominational stop levers 11 pivoted at 12 in a detachable frame 13, 60 said levers being actuated by devices comprising slide bars 14 and arms 15 secured to shafts 16 on which are also mounted tabulator lever arms 17 that, with the arms 15 and pivots or shafts 16, constitute bell cranks, 65 said bell cranks being mounted on a detachable frame 18 at the front of the machine. The lever arms 17 are provided with tabulator keys 19, and when one of the keys 19 is depressed it projects the upper end of the associate denominational lever 11 into the path of the column stops and also operates to release the carriage from the control of its escapement mechanism. The carriage releasing devices comprise a bail 20 arranged 70 behind the lower ends of the levers 11 and operative thereby. Said bail is pivoted at 21 on the frame 13 and is connected by devices comprising an arm 22 and a link 23 with the usual lifting device, not shown, 75 that disengages the carriage feed rack from the feed pinion.

In the Monarch machine a stationary holder or magazine 24 is provided in which the column stops 10 are stored, said stops 80 being transferred from the magazine to the stop bar 9 and retracted from said stop bar to the magazine by key controlled setting and retracting devices. The stop setting devices comprise a slideable block 25 mounted in a vertical groove at the left end of the stop magazine and connected by an angular link 26 with a bell crank 27 that is operative by a rod comprising two parts 28 and 29. The part 28 is the rod proper and at its 85 forward end is threaded to co-operate with the threaded bore of the part 29 which is in the form of a tube or stem which is provided at its forward end with a key or button 30. The threaded engagement of the two parts 90 28 and 29 of the key rod provides for a relative adjustment between them. The threaded portion of the rod 28 also receives a check nut 31 which co-operates with the end of the tube 29 to hold the parts 28 and 29 95 in set relationship. The tube or part 29 passes forward through holes in the ribs of the left-hand front post 2. These holes, which are indicated at 32, Fig. 2, resemble key-hole slots having round body portions 100 105 110

and narrow connected portions 33 having horizontal parallel walls. The stop retracting devices comprise a block 34 that is mounted to slide in a vertical guideway behind the block 25, the block or retractor being connected by an angular link 35 with key-operated devices not herein shown but corresponding with those above described for the stop setting mechanism. It is not thought necessary to describe in further detail the stop setting and retracting mechanisms nor to explain their operation, since the parts correspond with and operate like those found in the Monarch tabulating mechanism. It need only be said that when the key 30 is pushed in it operates through the bell crank 27 and link 26 to lower the block 25, which block, acting on the left-hand stop 10 within the magazine, pushes said stop downward on to the column stop bar 9. A spring 27^a restores the key 30 and its train of connections to normal position. Thus a plurality of stops may be set at desired positions along the column stop bar by operation of the key 30, the carriage being properly spaced between operations. Similarly after the tabulating operations are finished the stop retracting key may be operated to clear the stop bar 9 and restore the stops 10 to the magazine.

One drawback to the employment of stop controlling devices for ejecting tabulator stops from the magazine and retracting them from the stop bar into the magazine is that for one reason or another, such as improper actuation of the mechanism, the stop may be only partially ejected or retracted, leaving it partly in the magazine and partly on the stop rod so that if the carriage be moved with the stop in this position the carriage is likely to become jammed and the stop distorted. In order to minimize the improper or imperfect actuation of the mechanism, full stroke devices, as they are called, are provided, the purpose of these devices being to insure a full and complete actuation of the key or keys governing the stop controlling mechanism. The principal object of my present invention is to provide new and improved full stroke devices and further to provide key actuated means for releasing or throwing such full stroke devices out of use at will prior to the completion of the full stroke, a result which is believed to be entirely novel. My novel full stroke devices comprise a sleeve or tube 36 which, as best shown in Fig. 6, fits loosely over the key stem 29. The sleeve 36 is substantially the same length as the stem and is confined between the rear face of the key button 30 and the check nut 31, which serves to jam the sleeve against the key button and hold it in fixed relationship with the two-part member 28, 29. The sleeve 36 fits slidably in the holes 32 on the left-hand front post 2 and

thus provides a bearing for the push or key rod 28, 29. The top of the sleeve is formed with a series of teeth 37 providing a ratchet, while projecting from the right-hand side of said sleeve are two ribs or fins 38 and 39, 70 these ribs fitting slidably in the narrow horizontal portions 33 of the slots 32, the construction insuring the sleeve against accidental turning on its support, viz., the tube 29, the result being that the ratchet 37 is 75 always at the top of the sleeve and the ribs or devices 38 and 39 always at its right-hand side. Coöperative with the sleeve 36 is a pawl member which is in the form of a three-armed lever 40 (Figs. 3-5), said lever 80 being pivoted at 41 on a lug 2^a on the front post above the sleeve. The lever 40 comprises three substantially radially disposed arms 42, 43 and 44. The arm 42 inclines downward and rearward and is forked or 85 bifurcated, the body of said arm being twisted so that the forked portion fits over or straddles loosely the sleeve 36. The two arms or forks 42^a of the bifurcated portion extend downward parallel with each other 90 at the sides of the sleeve, the right-hand arm 42^a being disposed between the two ribs 38 and 39. The lower edge of the part connecting the forks or arms is bevel sharpened, as indicated at 45, to provide a tooth that co-95 operates with the ratchet teeth 37. These ratchet teeth incline from front to rear so that when the tooth 45 is engaged with the ratchet forward movement of the push rod 28, 29 is prevented, the ratchet and the 100 toothed arm 42 providing coöperating locking devices for this purpose. The arm 43 extends rearward and its end is formed with a double bevel or sharpened to coöperate with the bent or V-shaped free end of a detent spring 46, the lower portion of which is U-shaped and fits around the rear rib of the post 2, passing through a slot in said rib indicated at 2^b and being secured at its rear by a screw 47. The arm 44 projects forward 105 through a slot or opening 48 in the forward rib of the post 2, said arm 44 being fashioned to provide a finger piece or key for manipulating the member 40. 110

It will be noted that the arm 43 is engaged with the under side of the V-shaped end of the spring 46 and that the wide tooth 45 of the arm 42 is engaged with the ratchet 37, the rear end of the device or rib 38 being contiguous to the outer or right-hand arm 120 42^a. In operation when the key 30 is pressed in to eject a stop 10 from the magazine on to the stop bar, the toothed arm 42, co-operating with the ratchet 37, will prevent retraction or return movement of the key 125 30 after its actuation has once been begun, until the full actuation of the key has been completed, whereupon the rear end of the rib 39, coöperating with the right-hand arm 42^a, will turn the member 40 on its pivot. 130

As a result of this turning the tooth 45 will be swung up automatically out of engagement with the ratchet 37 while the arm 43 will be swung to the upper side of the V-end of the spring 46, which will coöperate with said arm to hold the member 40 in its inoperative position. It will further be noted that the automatically operating device or rib 39 forces the arm 42^a into contact with the rear rib of the post 2, which thus serves as a stop to limit rearward movement of the key 30 and connected parts. If the key 30 be now released it will be restored to normal position along with the train of devices which it actuates, this restoration being largely accomplished by the return spring 27^a. As the parts near the end of their return movement the rib 38, coming in contact with the arm 42^a will automatically swing the member 40 back to the Fig. 3 position, where the tooth 45 will again be ready for coöperation with the ratchet 37.

Sometimes, as when parts become jammed, the key 30 can be pressed in only part way, and it is desirable in such event to restore the key to normal position before again actuating it. In such event the finger piece or release key 44, which is conveniently arranged at the front of the machine and in juxtaposition to the key 30, affords a ready means for at will throwing the full stroke or key locking devices out of action; that is, assuming that the key 30 has been pushed in half way and it is desired to restore it to its forward position, the operator presses down the key 44 from the Fig. 3 to the Fig. 4 position, thus throwing out the locking tooth 45.

It will be observed in connection with my invention that in order that the parts 40 and 36 should properly coöperate, they must normally be maintained in a certain relationship, as in Fig. 3, the same being true of their abnormal or Fig. 4 relationship; while at the same time it is necessary in assembling the mechanism to vary the relationship between the key 30 and the rear part of the train that it controls. My improvements afford a ready means of accomplishing such adjustment and variation without affecting the relationship of the parts 40 and 36, it being only necessary to loosen the check nut 31 and turn the rod 28 in or out to the necessary extent. There is thus provided a construction which avoids lost or waste motion since the parts can be adjusted to throw out the full stroke lock at once on completion of the stop adjusting operation. Also my improvements may be applied to existing constructions without alteration of such constructions, said improvements comprising essentially the sleeve 36 provided with the ratchet 37 and the devices 38 and 39 for automatically controlling the pawl member 40, besides said pawl member itself.

While I have described my invention in

connection with the stop ejecting devices of the stop controlling mechanism it will be understood that said invention readily may be applied to stop retracting devices as well.

It will be observed that by my present invention there is provided in connection with the tabulating mechanism of a type-writing machine full stroke devices and a release key for at will rendering said full stroke devices inoperative; that full stroke devices are provided in combination with key actuated devices for controlling the column stops in their to and fro movements between the stop magazine and the stop bar; that said full stroke devices are automatically controlled and that hand actuated means, comprising a release key, is provided for also controlling the full stroke devices; that the full stroke devices have the additional function of a stop to limit the movement of the key actuated devices; that said full stroke devices operate to lock the key of the stop controlling devices until its stroke is entirely completed but that a separate key may be operated to release the locking devices prior to the completion of said full stroke; that the full stroke devices comprise ratchet teeth formed on a reciprocatory part or slide rod in combination with a locking pawl or lever which is settable in connection with the detent spring; that said lever in the present instance is provided with three arms, one serving as a finger piece or key; that said key is at the front part of the machine where it may be conveniently manipulated; and that the push rod aforesaid comprises two relatively adjustable parts so that said ratchet teeth which have an unvarying relationship with one of said parts may be maintained, while the relationship of said part in respect to the other devices in the train of mechanism may be varied as found necessary in assembling the mechanism.

Various changes may be made without departing from my invention.

What I claim as new and desire to secure by Letters Patent, is:

1. In tabulating mechanism for typewriting machines, the combination of a stop magazine, a stop bar, stops, key actuated devices for controlling said stops in their movements between said magazine and said stop bar, devices becoming automatically effective, after said key actuated devices are started, to lock said key actuated devices against retraction until the key stroke is completed, means for automatically releasing said locking devices, and hand actuated means for also releasing said locking devices.

2. In tabulating mechanism for typewriting machines, the combination of a stop magazine, a stop bar, stops, key actuated devices for controlling said stops in their

movements between said magazine and said stop bar, devices becoming automatically effective, after said key actuated devices are started, to lock said key actuated devices 5 against retraction until the keystroke is completed, means for automatically releasing said locking devices, and a separate key that may be operated to release said locking devices prior to the completion of the full 10 stroke of said key actuated devices.

3. In tabulating mechanism for typewriting machines comprising stop ejecting and retracting devices, the combination of a key, a train of connections between said key 15 and certain of said devices, said train comprising a reciprocatory part, a set of full stroke devices associated with said key and comprising a locking lever that is automatically set in operative and inoperative positions by the action of devices on said reciprocatory part, and a key for setting said lever at will.

4. In tabulating mechanism for typewriting machines, full stroke devices for the 25 stop controlling mechanism comprising a locking pawl and automatic means for throwing said pawl into and out of use, said pawl being provided with a key by which it may be thrown out of use at will after the beginning 30 of the operation of said stop controlling mechanism.

5. In tabulating mechanism for typewriting machines comprising stop ejecting and retracting devices, the combination of a key, 35 a train of connections between said key and certain of said devices, said train comprising a reciprocatory part, a set of full stroke devices associated with said key and comprising a locking lever that is automatically 40 set in operative and inoperative positions by devices on said reciprocatory part, ratchet teeth on said reciprocatory part, said lever being provided with a tooth that co-operates with said ratchet teeth, a detent spring for 45 holding said lever in and out of operative position, and a separate key for setting said lever out of operative position at will.

6. In tabulating mechanism for typewriting machines comprising stop ejecting and 50 retracting devices, the combination of a key, a train of connections between said key and certain of said devices, said train comprising a reciprocatory two-part member, said parts being relatively adjustable, a toothed member 55 having a fixed relationship with one of said parts, a pawl member adapted to co-operate with said toothed member, automatic means for throwing said pawl into and out of engagement with said toothed 60 member, and a finger piece on said pawl for controlling it independently of said automatic means.

7. In tabulating mechanism for typewriting machines comprising stop ejecting and 65 retracting devices, the combination of a

key; a train of connections between said key and certain of said devices, said train comprising a reciprocatory two-part member, and a locking nut holding the parts of said member in fixed relationship; a sleeve 70 provided with ratchet teeth and projections, said nut co-operating to set said sleeve on said member; a forked pawl loosely embracing said sleeve and co-operative with said ratchet teeth; a double acting detent spring 75 co-acting with said pawl, said projections operating automatically on said pawl to move it in and out of operative relationship with said ratchet teeth, and a finger piece at the front of the machine operative on said pawl for throwing it out of use at will.

8. In tabulating mechanism for typewriting machines, the combination of a stop magazine, a carriage provided with a stop bar, stops, devices for controlling said stops 85 in their to and fro movements between said magazine and said stop bar, said devices comprising a push rod provided with a key and also with ratchet teeth, a detent spring, and a lever having three arms, one serving 90 as a finger piece, another co-operating with the detent spring, and the third arm co-operating with said ratchet teeth.

9. In tabulating mechanism for typewriting machines, the combination of stop setting and retracting mechanism including a key rod, and full stroke devices comprising 95 a pawl member, and a member detachably mounted on said key rod and provided with ratchet teeth and means for throwing said pawl into and out of engagement with said ratchet teeth.

10. In tabulating mechanism for typewriting machines, the combination of stop setting and retracting mechanism including 105 a key rod, and full stroke devices comprising a pawl member, a sleeve provided with ratchet teeth and projections or ribs, said sleeve co-operating with said pawl, and means for detachably securing said sleeve 110 on said rod.

11. In tabulating mechanism for typewriting machines, the combination of stop setting and retracting mechanism including 115 a key rod, and full stroke devices comprising a toothed member and devices spaced along said rod for automatically operating said toothed member, said toothed member also co-operating with certain of said spaced devices to arrest said rod.

12. In tabulating mechanism for typewriting machines and in stop ejecting devices therefor, the combination of a stop magazine, a carriage, a stop ejector, devices for controlling the same comprising a push rod provided with a key, and also with ratchet teeth, a detent spring, and a three-armed lever, one arm of said lever being provided with a tooth adapted to co-operate with said ratchet teeth, another arm of said 125 130

lever having faces adapted to coöperate with said detent spring, and the third arm of said lever being employed as a finger piece.

5 13. In tabulating mechanism for typewriting machines and in stop ejecting devices therefor, the combination of devices for controlling the stop ejector comprising a push rod provided with a key, said push 10 rod being also provided with ratchet teeth; a detent spring; a three-armed lever, one arm of said lever being provided with a tooth adapted to coöperate with said ratchet teeth, another arm of said lever having faces

adapted to coöperate with said detent 15 spring, and the third arm of said lever being employed as a finger piece for setting said three-armed lever at will in inoperative position; and devices on said push rod for automatically controlling said three-armed 20 lever.

Signed at Ilion, in the county of Herkimer and State of New York this 12th day of April, A. D. 1917.
